(57) **CLAIM**

The ornamental design for a drywall tape mud applicator, as shown and described.

DESCRIPTION

FIG. 1 is a perspective view of my new design.

FIG. 2 is a perspective view of the design shown installed in a bucket.

FIG. 3 is a left side elevation view thereof.

FIG. 4 is a right side elevation view thereof.

FIG. 5 is a front elevation view thereof.

FIG. 6 is a rear elevation view thereof.

FIG. 7 is top plan view thereof; and,

FIG. 8 is a bottom plan view thereof.

The dashed lines showing the bucket and drywall tape are for illustrative purposes only and form no part of the claimed design.
